WHEEL ASSEMBLY FOR SUITCASES
OR THE LIKE

Francis W. Davis, Belmont, Mass.

Application October 1, 1949, Serial No. 119,154

1 Claim. (Cl. 280—39)

1 This invention relates to a wheel assembly adapted to be mounted on articles to be transported, such as suit-cases or the like. Since a packed suit-case, especially of large size, is usually of sufficient weight to make it difficult for the average person to carry, various schemes have been devised for mounting it on wheels so that it can be trundled with far less effort. Such devices must necessarily project beyond the contour of the suit-case when in use, but should be partly or wholly retractile so that the stowage space required by the suit-case will not be increased excessively by reason of projecting devices. On the other hand, it is desirable also that not too much of the cubic capacity of the suit-case be devoted to housings for such devices, as that reduces by so much the space available for articles to be packed therein.

According to the present invention, wheels are provided on brackets which can be folded with the wheels against a surface of the suit-case so that they will project a minimum distance from the suit-case consistent with being wholly outside of the normal contour of the suit-case. The folding brackets are furthermore detachably mounted on plates which are easily and permanently secured to the outside of the case. The plates, brackets and wheels can thus be sold and used as an accessory which can be mounted readily on a case by the use of ordinary tools and without any alteration of the case itself other than the drilling of some holes for screws or rivets to secure the anchor plates.

For a more complete understanding of the invention, reference may be had to the following description thereof and to the drawing, of which—

Figure 1 is a side elevation of a suit-case with an embodiment of the invention attached thereto, in position for use;

Figure 2 is a front elevation of the same;

Figure 3 is a side elevation, on a larger scale, of one of the wheel assemblies embodying the invention;

Figure 4 is an end elevation of the same, the folded position being indicated in dotted lines;

Figure 5 is a section on the line 5—5 of Figure 3; and

Figure 6 is a fragmentary elevation of the assembly viewed from the end opposite to that shown in Figure 4.

The invention is illustrated and is hereinafter described as applying to a suit-case, but it is evident that it can be used with other equivalent articles.

2 A suit-case 10 is shown in Figures 1 and 2, this case having attached thereto a pair of wheel assemblies embodying the invention. One such wheel assembly is illustrated in Figures 3 and 4 and comprises an anchor plate 12 which, as indicated in Figure 5, has converging side edges. Along these side edges the margins are bent inward to form inturned flanges 14 and 16. This anchor plate is provided with a couple of holes 18 through which suitable fastening elements, such as screws, bolts or rivets, may be inserted to secure the plate permanently to a wall of the suit-case 10 or to an end of the top of the case, as indicated in Figure 2.

The anchor plate is intended to receive and hold a base plate 20 having converging side edges adapted to slide in under the bent-over margins 14 and 16 of the anchor plate 12. To prevent looseness between the base plate and the anchor plate, a suitable number of bosses 21 are swaged at the side margins of the base plate to increase the effective thickness of the margins so that they will have a snug fit in the channels formed by the inturned flanges 14 and 16 of the anchor plate.

By two transverse cuts extending half-way across the base plate, a strip is formed which is bent up to form a hinge leaf 22 extending perpendicularly from the plane of the base plate. The end portion 23 of this strip is curled into tubular form to receive a hinge pin 24. The other hinge leaf is a part of a bracket 26 which may be made of two sheet metal blanks suitably shaped, then welded or riveted together. These blanks have complementary semi-cylindrical portions which oppose each other to form tubular elements 28 and 30 to receive the hinge pin 24. To hold the pin in place, it may have a binding fit in any one of the tubular elements 23, 28 or 30. Portions of the plates of the bracket 26 extend beyond the hinge pin and are shaped to form a locking nose 36. Other portions of these plates form arms 32 and 34 of a fork between which is revolubly mounted a wheel 40 by suitable means such as a short shaft 41.

The base plate 20 has an extension 42 at the smaller end thereof, bent at right angles to the plate itself. This extension has a rectangular aperture 44 therein which is adapted to receive the nose 36 so as to lock the bracket 26 in a position in which the plane of the bracket is perpendicular to the plane of the base plate 20. This is the position shown in Figures 1 to 4.

As indicated in Figure 3, a gap is left between 55 the tubular portion 23 of the base plate and the

3

tubular portion 28 of the bracket 26. Within this gap a compression spring 46 is loosely mounted on the pin to press the bracket toward the extension 42 of the base plate so as to maintain the nose 36 in the hole 44. When it is desired to swing the bracket 26 to a position approximately parallel to the base plate, as indicated in broken lines in Figure 4, the locking nose 36 can be disengaged from the hole 44 by pushing the bracket 26 manually along the axis of the hinge pin so as to compress the spring 46. When the bracket is then rocked in one direction or the other and released, the locking nose will engage under the lower edge 48 of the extension 42 to hold the bracket and wheel assembly in its folded position against the face of the suit-case. When the bracket and wheel assemblies are thus folded against the case, they project to a very short distance therefrom and, hence, the extra stowage space required by the suit-case is relatively small.

The bracket and wheel assembly is detachably locked in place on the anchor plate 12 by a suitable elongated wire spring 50 which is mounted on the base plate, as indicated in Figures 5 and 6. This spring has an end portion which is gripped in a struck-up loop 52 of the base plate. The other end portion is curled like a pig's tail at 56, the extremity 58 of the spring projecting parallel to the axis of the curl to engage as a latch in a notch 60 in the edge of turned flange 16 of the anchor plate. The latch 58 can be disengaged from the notch 60 either horizontally or vertically. Pressure of a finger tip against the coil 56 will readily move the latch 58 horizontally so from the notch 60 to release the base plate so that the wheel and bracket assembly can be removed from the anchor plate. When the base plate is inserted in between the turned flanges 14 and 16, the latch 58 meets the end edge of the flange 16, is cammed vertically downward so that it slides along the under face of the flange until it gets to the notch 60, whereupon it springs up into the notch to lock the base plate in place. The length of the spring 50 makes it easy to displace the latch 58 horizontally from the notch 60 by pressure against the coil 56. To prevent

4

too easy vertical displacement of the latch from the notch, the spring is stiffened in that plane by a confining tongue 62 which is struck up from the base plate and engages the spring 50 near its mid-point.

By mounting anchor plates on a number of suit-cases, the wheel assemblies can be shifted from one suit-case to another in a few moments. When the assemblies have been removed from the anchor plates, the latter occupy a negligible additional space.

I claim:

A wheel assembly for a suit-case or the like, comprising a flanged anchor plate, a base plate having an intermediate portion bent out of the plane of the base plate and curled to form a hollow cylinder parallel to the longitudinal axis of the base plate, said base plate also having an end flap bent at right angles to the plane thereof and with a hole therein, a bracket consisting of two preformed pieces of sheet metal permanently secured together, said pieces being formed to provide two aligned hollow cylinders to act with the hollow cylinder of the base plate as hinge elements, a hinge pin fitted in the three said cylinders, said metal pieces also including a locking nose normally engaged in said hole and a pair of spaced parallel arms, a wheel revolvably mounted between said arms, spring means yieldingly maintaining said locking nose in said hole, and a spring mounted on said base plate and releasably engaging said anchor plate to lock the wheel assembly together.

FRANCIS W. DAVIS.
